UNITED STATES PATENT OFFICE

106,671

DESIGN FOR AN ADVERTISING NOVELTY

Herbert N. Mace, Terre Haute, Ind.

Application September 10, 1937, Serial No. 71,557

Term of patent 14 years

To all whom it may concern:

Be it known that I, Herbert N. Mace, a citizen of the United States and resident of Terre Haute, county of Vigo, and State of Indiana, have invented a new, original, and ornamental Design for an Advertising Novelty, of which the following is a specification, reference being had to the accompanying drawing, forming part thereof.

Fig. 1 is a side perspective view of an advertising novelty, showing my new design; and Fig. 2 is a reverse side perspective view thereof.

I claim:

The ornamental design for an advertising novelty, as shown.

HERBERT N. MACE.
